UNITED STATES PATENT OFFICE.

WILLIAM L. OAKES, OF DECATUR, ILLINOIS.

FEED-WATER HEATER.

SPECIFICATION forming part of Letters Patent No. 367,839, dated August 9, 1887.

Application filed April 11, 1887. Serial No. 234,364. (No model.)

To all whom it may concern:

Be it known that I, WILLIAM L. OAKES, of the city of Decatur, county of Macon, and State of Illinois, have invented certain new and useful Improvements in Feed-Water Heaters and Purifiers, of which the following is a specification.

The object of my invention is to increase the effectiveness of feed-water heaters both generally and specifically; and I attain my object by means of the combinations, sub-combinations, details of construction, and relative arrangements of parts, hereinafter set forth in detail, and specifically claimed.

15 In the drawings accompanying and forming a part of this specification, Figure 1 is a central vertical section of my device, and Fig. 2 is a horizontal section on dotted line *x* in Fig. 1.

The casing-cylinder *A* is divided in three 20 compartments—namely, steam-chamber *B*, settling-chamber *C*, and hot chamber *D*. The settling-chamber is at the lower portion of the cylinder and has a dished bottom, *m*, from the lowest surface of which the blow-off pipe *n* extends. The steam-chamber is above the settling-chamber and contains the vertical water-pipes *a*, which connect the settling-chamber with the hot chamber. The hot chamber is 25 above the steam-chamber, and is formed of a basin, *g*, detached, except at its upper rim, from the casing-cylinder. Exhaust-steam is admitted to the steam-chamber through vertical pipe *c*, which extends through the center of the settling-chamber and terminates near 30 the longitudinal center of the steam-chamber. The escape-pipe *d* for the exhaust-steam extends downward from the lowest portion of the steam-chamber and encompasses the feed-pipe *c*.

40 Water is conducted to the settling-chamber through pipe *i*, passes through pipes *a* to the hot chamber, and is ultimately discharged through pipe *b*, which extends downward through the exhaust-steam feed-pipe *c*, and 45 connects with the boiler in any suitable manner. The cap *s* of the hot chamber is internally concaved and externally recessed, and is provided at its center with an opening with which safety-valve *p* and discharge-valve *q* are connected. Plate *u* combines with the recessed cap to form space *f*, which is intended 50 to lessen the radiation of heat, and which may

be filled with any suitable non-conductor, atmospheric air being preferred.

The hand-hole *r* provides ready access to 55 the settling-chamber. Valve *o* regulates the discharge of blow-off pipe *n*. Check-valve *l* and stop-valve *k* provide means for effectually controlling the supply of water. Lower head, *e*, of the steam-chamber forms a basin for the 60 collection and immediate discharge of water condensed from the exhaust. Upper head, *f*, forms the bottom for the hot chamber. The exhaust-pipes *c* and *d* terminate in a connection-chamber, *E*, having partition *g'*, separating the openings *e'* and *d'* of the different pipes, and also having flanges *h*, with which the conducting-pipes connect.

The outlet-pipe *d* connects with the upper portion of the connection-chamber. The inlet-pipe *c* connects with the partition. The connection-chamber is secured to the bottom of the settling-chamber by a series of circularly-arranged bolts, which permit the connection-chamber to be rotatably adjusted. The 75 outlet-pipes *b* and *d* are secured rigidly at their upper ends in their respective bearings and have packing-connections at their lower ends, as indicated in the drawings.

In operation, water is first fed to the settling-chamber at the bottom of the cylinder, where the lowest temperature will naturally exist, and is warmed therein to some extent. Passing upward through pipes *a*, more direct contact with the exhaust is had and the temperature is considerably raised. In the hot chamber, which is almost entirely surrounded by the hottest exhaust and protected from radiation, heat is rapidly generated, and the temperature is raised to the highest possible degree in the narrow discharge-pipe, which is in direct contact on all sides with exhaust-steam fresh from the steam-cylinder.

The discharge *d* at the bottom of the steam-chamber insures the constant discharge of water formed by condensation of exhaust, which would otherwise have a tendency to cool the lower connections of pipes *a* and induce leakage by the consequent contraction.

The discharge-valve *q* provides means for 100 blowing off any scum that may accumulate in the concavity of the cap, and the simplicity of the internal construction of the settling-chamber and its ready accessibility through the

hand-hole form, with blow-off pipe n , complete provision for the removal of sediment.

The rotative adjustment of the connection-chamber enables connections to be made from any direction relative to the hand-hole and lateral pipes, which is a matter of great convenience in setting up heaters in angles, nooks, and other places, where free access to all parts of the heater may not be had.

10. The packing-joints at the lower ends of the discharge-pipes provide for independent contraction and expansion therein, such provision being especially desirable for the water-pipe, which, from its length and direct exposure to heat, is apt to become unduly extended while the feeder is in operation.

I claim as new and desire to secure by Letters Patent—

1. A feed-water heater comprising a lower settling-chamber, an upper hot chamber, and an intermediate steam-chamber, pipes in the steam-chamber connecting the settling-chamber with the hot chamber, a steam-inlet pipe extended upward through the settling-chamber and into the steam-chamber, and a water-outlet pipe extended from the hot chamber through the steam-chamber and settling-chamber in longitudinal contiguity with the steam-inlet pipe.

30. 2. A feed-water heater comprising a lower settling-chamber, an upper hot chamber, and an intermediate steam-chamber, pipes in the steam-chamber connecting the settling-chamber with the hot chamber, a steam-inlet pipe connecting with the steam-chamber, and a water-discharge pipe extending from the heater through the steam-inlet pipe.

35. 3. A feed-water heater comprising a lower settling-chamber, an upper hot chamber, and an intermediate steam-chamber, pipes in the steam-chamber connecting the settling-chamber with the hot chamber, a steam-inlet pipe extended vertically through the settling-chamber and into the steam-chamber, and a water-discharge pipe extended from the hot chamber through the steam-chamber and through the steam-inlet pipe.

40. 4. A feed-water heater comprising a lower settling-chamber, an upper hot chamber, and an intermediate steam-chamber, pipes in the steam-chamber connecting the settling-chamber with the hot chamber, a steam-outlet pipe extending from the steam-chamber through the settling-chamber, a steam-inlet pipe entering the steam-chamber through the steam-outlet pipe, and a water-discharge pipe extended from the hot chamber through the steam-inlet pipe.

45. 5. A feed-water heater comprising a water-chamber and a steam-chamber, both having inlet-pipes and outlet-pipes, the outlet-water pipe being encompassed by the steam-inlet pipe throughout a portion of its length.

60. 6. A feed-water heater comprising a water-chamber and a steam-chamber, both having inlet-pipes and outlet-pipes, the steam-outlet pipe encompassing a portion of the steam-in-

let pipe and the steam-inlet pipe encompassing a portion of the water-outlet pipe.

7. In feed-water heaters, in combination, the lower settling-chamber having the centrally-depressed bottom and the blow-off pipe, the upper hot chamber connected with the settling-chamber by the vertical pipes, the intermediate steam-chamber having its outlet-pipe 75 extended through the settling-chamber and its inlet-pipe extended through the outlet-pipe, and the water-outlet pipe extended from the hot chamber through the steam-inlet pipe.

8. In feed-water heaters, in combination, the lower settling-chamber having the centrally-depressed bottom, the blow-off pipe, the water-inlet, and the hand-hole, the upper hot chamber connected with the settling-chamber by the vertical pipes, the intermediate steam-chamber having its outlet-pipe extended through the settling-chamber and its inlet-pipe 85 extended through the outlet-pipe, and the water-outlet pipe extended from the hot chamber through the steam-inlet pipe.

9. In feed-water heaters, in combination, the cylinder having the lower settling-chamber, the upper hot basin having its lower portion disconnected from the cylinder, the intermediate steam chamber encompassing the lower 95 portion of the hot basin, pipes connecting the settling-chamber with the hot basin, a supply-pipe for the settling-chamber, a discharge-pipe for the hot basin, and an inlet and an outlet for the steam-chamber.

10. In feed-water heaters, in combination, the cylinder having the lower settling-chamber, the upper hot basin having its lower portion disconnected from the cylinder, the inwardly-concaved cap over the hot basin having 105 the central valve-opening, the intermediate steam-chamber encompassing the lower portion of the hot basin, the pipes connecting the settling-chamber with the hot basin, a supply-pipe for the settling-chamber, a discharge-pipe 110 for the hot basin, and an inlet and an outlet for the steam-chamber.

11. In feed-water heaters, in combination, the connection-chamber having the partition separating the steam-inlet opening from the 115 steam-outlet opening, the steam-inlet pipe connected with the partition, and the steam-outlet pipe encompassing the inlet-pipe and connecting with the outer surface of the connection-chamber.

12. In feed-water heaters, in combination, the connection-chamber having the partition separating the steam-inlet opening from the steam-outlet opening, the steam-inlet pipe connected with the partition, the steam-outlet pipe 125 encompassing the inlet-pipe and connecting with the outer surface of the connection-chamber, and the water-discharge pipe extending through the steam-inlet pipe and the connection-chamber.

13. In feed-water heaters, in combination, the connection-chamber secured to the heater in a manner permitting rotative adjustment, and provided with the partition separating the

steam - inlet opening from the steam - outlet opening, the steam-inlet pipe connected with the partition, and the steam-outlet pipe encompassing the inlet-pipe and connecting with 5 the outer surface of the connection-chamber.

14. In feed-water heaters, in combination, the lower settling - chamber, the upper hot chamber, and the intermediate steam-chamber, the pipes in the steam-chamber connecting 10 the settling-chamber with the hot chamber, suitable inlets and outlets for both steam and water, and a condensed water-drain pipe extending downwardly from the bottom of the steam-chamber.

15. In feed-water heaters, in combination, the lower settling - chamber, the upper hot chamber, and the intermediate steam-chamber, the inwardly-concaved and outwardly-recessed cap, the plate over the cap inclosing the 20 recess, the pipes connecting the settling-chamber with the hot chamber, a supply-pipe for the settling-chamber, an outlet-pipe for the hot chamber, and an inlet and outlet for the steam-chamber.

25. In feed-water heaters, in combination, an upper hot chamber, a lower settling-chamber, and an intermediate steam-chamber, pipes in the steam-chamber connecting the settling-chamber with the hot chamber, a steam-outlet 30 pipe extending from the steam - chamber

through the settling-chamber, a steam-inlet pipe entering the steam-chamber through the steam-outlet pipe, and a water-discharge pipe rigidly secured to the hot chamber and extended through a packing-connection at the 35 termination of the steam-inlet pipe, as shown and described.

17. In feed-water heaters, in combination, an upper hot chamber, a lower settling-chamber, and an intermediate steam-chamber, pipes 40 in the steam-chamber connecting the settling-chamber with the hot chamber, a steam-outlet pipe extended from the steam - chamber through the settling-chamber, connected rigidly at its upper end and in a manner permitting longitudinal expansion and contraction at its lower end, a steam-inlet pipe entering the steam-chamber through the steam-outlet pipe, and a water-discharge pipe rigidly secured in the hot chamber, extended through 45 the steam-inlet pipe and connected with the lower end of the same in a manner permitting longitudinal expansion and contraction, as shown and described.

In testimony whereof I sign my name in the 55 presence of two subscribing witnesses.
